UNITED STATES PATENT OFFICE.

FRANCIS W. JONES, OF NEW YORK, N. Y.

DYNAMO-TELEGRAPHY.

SPECIFICATION forming part of Letters Patent No. 433,082, dated July 29, 1890.

Application filed June 11, 1889. Serial No. 313,918. (No model.)

To all whom it may concern:

Be it known that I, FRANCIS W. JONES, a citizen of the United States, and a resident of New York, in the county of New York and State of New York, have invented certain new and useful Improvements in Dynamo-Teleg-raphy, of which the following is a specification.

My invention relates to arrangements of circuits and apparatus at a telegraph-office, and is of utility especially in those cases where the local and branch or loop circuits leading to branch offices are supplied with current from dynamo-machines.

The object of my invention is to provide a means whereby branch lines may be readily connected to local circuits, or local circuits may be interconnected, and the potential of the source feeding the lines may be automatically adjusted to the varied conditions occurring with the various connections.

The object of my invention is also to avoid the danger of damage to apparatus in local circuits from heavy currents passing from main lines to earth at the telegraph-station.

My invention consists in the combination, with a spring-jack of any usual construction, of a supplemental or auxiliary switch actuated by the wedge of the spring-jack and having contacts of different potential adapted, respectively, to the resistance of the normal local circuit and to the added resistance of the branch or loop line to be connected to the local, whereby on insertion of the wedge the switch may be automatically changed to connect the circuit to a source of different potential, as will be hereinafter set forth.

My invention consists, further, in the combination, broadly, with any spring-jack, of an electric switch actuated by the spring-jack wedge and electric apparatus of any description in a connection between the switch and jack and in a circuit formed normally through the switch and spring-jack, whereby on insertion of the spring-jack the connections of such circuit at the switch shall be automatically and simultaneously changed for any purpose.

My invention consists, also, in the particular combinations of apparatus and circuits, hereinafter described in connection with the accompanying drawings, and then claimed.

In the accompanying drawings, Figure 1 is a general diagram of circuits and apparatus embodying my invention. Figs. 2 and 3 illustrate the condition of parts of the apparatus when a local circuit is connected to a branch or loop circuit. Fig. 4 is a diagram illustrating the connection of local circuits of a duplex or quadruplex telegraph apparatus for the purpose of repeating from one line to another. Fig. 5 illustrates two sets of quadruplex telegraphs connected so that one line may repeat to the other, and shows, also, a branch-office line connected at the same time into the local circuits, so as to form in effect extensions of the sending and receiving locals. Fig. 6 illustrates a modification in the manner of securing a difference of potential at the contacts of the switch connected to the local circuit. Figs. 7 and 8 show, in side elevation and plan, respectively, modifications in the mechanical construction of the spring-jack. Figs. 9 and 10 show, in side elevation and plan, respectively, another modification. Fig. 11 shows a further modification in the manner of controlling the circuits of a resistance to secure difference of potential at the switch connected to the local circuit. Fig. 12 illustrates, in side elevation, a further mechanical variation in the construction of the spring-jack. Fig. 13 illustrates a modification in the spring-jack plug or wedge and the circuit connected thereto. Fig. 14 is a vertical section through one of the artificial resistance-tubes.

A and B indicate the local apparatus in the local sending and receiving circuits of two sets of duplex or quadruplex apparatus. Each set may be either that for the number one or number two side of a quadruplex telegraph. The main lines and connections with the relays and transmitters on such sets are omitted for the sake of clearness.

In each set A B, R indicates a relay; S, a sounder; T, the electro-magnet which operates the lever of a transmitter controlling the main-line current, and K a key in the local circuit with the electro-magnet of the transmitter T. The local containing the instruments S R is the receiving local, and the local containing the instruments T K is the sending local, of each set. The circuit for each sending or transmitting local is completed on

one side through the contact-jaws *a b* of a spring-jack of any usual or suitable construction, *a* being the fixed jaw to which one end of the local circuit is connected to earth, and
 5 *b* the movable jaw which is connected to earth or to a return-circuit. The other terminal of each local circuit connects with a switch *C*, adapted to be operated by the insertion of a wedge between the jaws of the
 10 spring-jack.

The switch *C* may be of any desired construction, its purpose being simply to change the potential of the current supplied to the local circuit passing through the spring-jack
 15 jaws, or, in case a wedge is inserted, to such circuit passing through the conductor connected to the wedge. A simple form of switch *C* consists simply of a spring mounted on the spring-jack lever, but insulated therefrom
 20 and adapted to play between two contact-stops *c d*, which I propose to make of different potential by connecting them to dynamo sources of different electro-motive forces. As will be presently described this difference of
 25 potential may be secured by cutting out or in artificial resistances. The normal contact, as *c*, of each switch *C* connects through an artificial resistance *R^s*, the purpose of which is to reduce the current supplied to the local
 30 circuit, so that the amount of current shall be, say, two-tenths of an ampère, more or less, as desired, but shall in any case be not so great as to injuriously heat the apparatus. Each resistance *R^s*, to which a contact *c* is connected, is connected at its opposite terminal to a bar or conductor *D*, secured beneath a suitable board and in turn connected directly or indirectly with one of a bank of dynamos *F*. In the present instance I have illustrated
 35 this connection as being made through one of a series of main conductors *G*, which in this case are supposed to connect a station at which the dynamos *F* are located, with the office at which the telegraph apparatus is located. The wires shown connecting the bars *D* with the conductors *G* are in this case simple leader-wires. The opposite contacts *d* of the switches *C* connect to the bars *G²* of a switch-board. Opposite each bar *G²* are
 40 placed a number of conductor-blocks *g*, adapted to be connected to bars *G²* by the insertion of plugs. The lower blocks *g* of the several switch-bars *G²* are shown so connected. The blocks *g* are connected through
 45 resistances *R^s* with the dynamos or with conductors *G*, which derive current from such dynamos. The various dynamos of the bank *F* are preferably of different potential, as indicated by the letters 48^v 24^v 12^v 6^v 2^v, the
 50 figures indicating the number of volts potential of each.

The resistances *R^s* in the several circuits are of different value, depending upon the volts potential of the machine in whose circuit they are placed, the design being in any case to cut down the current to the particular requirements of each of the several cir-

cuits connected to the same dynamo. By means of the switch-board described the higher potential dynamos may be changed to any spring-jack by suitable blocks. Thus, for instance, while the two-volt machine regularly supplies the normal points of the switches *C* to work the locals when each has its circuit completed independently of the others or of branch circuits, the other point of the switch *C* may be connected, by means of the switch-bars and pegs, to either of the dynamos of greater potential, according to the current required for the particular branch wire to be connected.

S² R² indicate respectively the sounder and the relay of a single Morse wire. The sounder and the relay contacts are in a local-circuit conductor from one of the resistances in the connection to the two-volt machine, and the connection is made, as shown, from the resistance through the sounder to the front contact of the relay. The relay-lever itself is connected directly to earth or to a return-wire. The purpose of this is to provide for the case of an accidental connection between the core of a relay and the main line helix, and a simultaneous connection of the armature-lever with the core, as frequently happens by adjustment of the core against the armature. In this condition, if a heavy current should pass over the main line and through the helix—as, for instance, a current of lightning—such current would pass directly to earth by way of the core and armature instead of passing over the local circuit and through the local dynamos to earth, as it might do if the order of connections were reversed and the relay-armature were connected to such local dynamo while its front stop were connected to earth.

H H² are bars of spring-jack wedges connected by a flexible cord. Each wedge is provided with a live or conducting and a dead or insulating length at the ends which are adapted to be inserted between the jaws of the spring-jack.

I indicates a branch office, from which wires 10 and 11 lead to the main office, said wires terminating, respectively, in other spring-jack wedges *H H²*, similar to those just mentioned and adapted for insertion in the jaws of each spring-jack. The wire 10 includes at the branch office an ordinary sounder, and is the wire for the receiving side of a duplex or quadruplex telegraph. The wire 11, including at the branch office a key and sounder, is the wire for the sending side, and is adapted, by means of its plug *H²*, to be connected at pleasure to the local sending-circuit of a duplex or quadruplex, so that said sending-wire will form in effect an extension of the local circuit, including the instruments *K T*. Under such conditions of connection it will of course be understood that the local circuit is closed by the operator who manipulates the key *K*. The means for so closing it is the ordinary switch connected with each key.

With the set B, I have shown other switches L L². The switch L is an ordinary two-point switch interposed between one side of the local circuit and the switch C, and forming in effect a switch by which the local circuit may be grounded and at the same time disconnected from the switch C and the dynamo. The switch L² is a switch in the ground or return connection from the movable jaw of the spring-jack. Its office is to open such connections under conditions to be presently described. The movable spring-jack jaw connects also, as shown, with a point of the switch L, such connection being in fact that which puts the switch L in connection with the ground through switch L².

By the connections of the switch C (indicated in Fig. 1 and already described) it is obvious that through point c the local circuit passing through the spring-jack may be in connection with a dynamo source of one potential, and through the contact-point d of said switch it may be put in connection with a dynamo of different potential—as, for instance, the six-volt machine—or, by properly changing the connections on the switch-board, may, through a block g near the strip G², be placed in connection with a source of even higher potential, according to the length and resistance of the branch circuit leading to the branch office, or according to the length and resistance of any other circuit which is to be made a continuation of the local circuit normally passing through the jaws of the spring-jack.

In the normal condition of the several spring-jack switches it will be seen that each dynamo-circuit passing through a switch C is completed through the local circuit and the jaws of a spring-jack to earth. In order to connect a branch office to the local circuits of a duplex or quadruplex set so that such branch office shall receive a message and be able to transmit a message in the same way as the main office, it is only necessary to insert the plug H H² of the wires 10 11 into the spring-jack jaws of either set A or B, as indicated in Figs. 2 and 3.

In Fig. 2 the branch office is shown connected to set A. In this case the insertion of the wedges operates the switches C, thus changing the connection of the local circuit to a dynamo of higher potential adapted to the increased resistance introduced by the connection of the branch line. The circuit of the six-volt dynamo is now in each instance through the contact-stop d, switch C, sounder and relay contacts, and block a of the spring-jack to the conducting side of the spring-jack wedge, and thence by the branch or local office wire to earth. The conducting side of each wedge breaks the direct connection to earth for the local circuit. If the connection of the branch office is to be made with a set B, having the switches L L², such switches are left in their normal position, and the condition of the circuits and apparatus is as indi-

cated in Fig. 3. If it is desired to connect two sets of duplex or quadruplex telegraphs so that the message received from one point may be retransmitted automatically to another through the sets of duplex or quadruplex connected, the spring-jack blocks H H² are inserted in the several spring-jacks in the manner indicated in Fig. 4, and the switches L, of one set are changed so as to place one side of the local circuits of such set into direct connection with the earth or return-wire, instead of leaving them in connection with their dynamo-machines and with the substitute dynamo, which is placed in connection with the local circuit by the action of the wedge H². The circuits of the two sets under these conditions may be readily traced as follows: The transmitting-local for set A is connected with a six-volt dynamo and the circuit passes by wedge H, inserted into the spring-jack for such local to the spring-jack H² of the receiving-local for set B, thence to the switch L of such set, and to earth. The additional potential of the six-volt dynamo substituted by the insertion of the wedge H now supplies the local of increased resistance, consisting of the two locals and the connecting-wires. In the same manner the receiving-local of the set A forms circuit through the transmitting-local of the set B, directly to earth. By this arrangement one set may repeat to another.

If it be desired that the condition of Fig. 4 be maintained and that at the same time the branch office may receive the message repeated from one set to the other, the wedges H H² of the branch-office lines are inserted in addition, after the manner indicated in Fig. 5, and the switches L² are turned to break the ground connection from the spring-jack lever. The switches L are maintained in the position shown as forming a connection from the spring-jack lever to the local circuit. If it be supposed that the sets A B are at an office—say, New York—and that set A is connected to Philadelphia while set B is connected to Boston, then with the wedges H H² inserted as shown the branch office will receive the message repeated from Boston to Philadelphia through the local apparatus. The circuit for the sending side of the branch office will then be—starting from the signal side of the office A—from a six-volt dynamo through the receiving-local of set A by way of the connected wedges to the transmitting-local of the set B, to switch L, to the spring-jack lever, to the conducting side of wedge H², and to and through the branch office. The receiving side will be in the local circuit formed through the sending side of set A and the receiving side of set B in a similar way, the branch line forming the receiving side being made in effect an extension of the connected locals of A and B through the contact of the conducting side of the wedge H with the spring-jack jaw, a condition made possible by the turning of the switch L² to break the

direct ground connection from one side of the lever through the switch L, and it exists in the arrangement shown in Fig. 4.

The adjustment of potential, secured automatically by the operation of the switch C when the wedge is inserted, might be obtained with the arrangement shown in Fig. 6, where the two points of the switch are connected with the same dynamo, but through paths of different resistance, the point c being connected through an artificial resistance R^3 of some considerable amount, and point d being connected directly with the dynamo. In the condition shown it is obvious that the potential at the point c, when the local circuit is completed directly through the spring-jack jaws, is less than it is when the branch circuit is connected as an extension of said local and the switch is at the same time turned to the point d, which, being connected directly to the dynamo, is of greater potential. It is obvious also that the same effect might be obtained by simply shunting out resistance after the manner indicated in Fig. 11, the point d being connected to the dynamo independently of the resistance R^3 , which latter is constantly in circuit, but is shunted when the wedge is inserted.

Other mechanical constructions of spring-jack and switch might be used—as, for instance, such as that indicated in Fig. 12, where the switch C is a spring placed in position to be engaged by the wedge directly and to have a contact carried by said spring C forced over against a contact d, by means of which the resistance is shunted.

Another mechanical construction adapted to the purpose is indicated in Figs. 7 and 8, where the switch-lever C is a separate lever of insulating material pivoted beside the spring-jack lever and adapted to be engaged by the wedge on insertion for operating the spring-jack, or such switch C might consist of a spring carried directly by the spring-jack lever on the side thereof, as shown in Figs. 9 and 10, and adapted to play between the two contact-stops c d, which in this instance would be reversed in position from the position indicated in Fig. 1.

While my construction of spring-jack and switch and connections of the same are especially useful in those cases where telegraph apparatus is included in the circuit formed through the switch and spring-jack, I do not limit myself to such use of the same, but design to include any apparatus placed in the said connection and employed under conditions where it is desirable to include the same at pleasure in connection with another circuit of added or different resistance or requirements.

A convenient way of mounting the artificial resistance R^3 is shown in Fig. 14. The resistance-wire may be made of German silver and is double wound, as indicated, to remove self-induction. It is wound upon a

tube of tin open at the top and having ventilating-openings near its bottom, as indicated at t, which permit the ingress of air and circulation of the same to the interior of the tube to keep the same cool in case the resistance should heat abnormally. The tube is mounted upon a suitable board, to the bottom of which is secured the conductor D. Binding-posts P Q are provided on the board and serve for the attachment of the terminals of the artificial resistance. To the binding-post Q may be attached at pleasure the leading-wires, which are carried to the switch-board. The binding-post P is in direct electrical connection through the board with the conductor D, which extends beneath the same and to which the binding-post of the other resistances upon the same board are simultaneously connected. 85

What I claim as my invention is—

1. In an electric switch, the combination, with the spring-jack, of a supplemental switch connected to the normally-open contact-point and arranged, upon insertion of the wedge, to place in circuit generators of varying potential, and one or more wedges, to which are connected loops, relaying-circuits, and branch circuits, arranged to automatically cut out grounds and extend the circuit, all substantially as shown and described. 95

2. The combination, with a spring-jack, of a supplemental switch device actuated by the spring-jack wedge and having two contacts of different potential, as and for the purpose described. 100

3. The combination, with a spring-jack, of a supplemental switch actuated by the spring-jack wedge and sources of electricity of different electro-motive force connected to different contacts of said switch. 105

4. In an electric switch, the combination, with a spring-jack, of resistances electrically connected in circuit between said jack and the generator while said jack is in a normal condition, and a wedge arranged to insert additional circuits and at the same time cause said spring-jack to close on a contact-point connected directly to the generator, thus automatically cutting out said resistances, substantially as shown and described. 115

5. In a dynamo-telegraph system, the combination, with local receiving and transmitting circuits containing, respectively, relay-magnets and the actuating-magnets for transmitters, of spring-jacks, through the jaws of which the said local circuits are normally completed, and pairs of spring-jack wedges electrically connected by a flexible conductor and having each live and dead sides opposite one another, as and for the purpose described. 120

6. The combination, substantially as described, of local receiving and transmitting circuits, of spring-jacks through which said circuits are normally completed, two-point electric switches actuated by the spring-jack wedges, generators of different potential con- 130

- nected to opposite points of the switches, and flexible conductors connecting the pairs of the spring-jack wedges.
7. The combination, with a local circuit and 5 spring-jack through the contact-jaws of which said local is normally completed, of a supplemental switch actuated by the spring-jack wedge and having opposite insulated contacts, generators of different potential connected respectively to said contacts, and a branch or separate office-circuit having connection to the spring-jack wedge, as and for 10 the purpose described.
8. In an electric switch, the combination, 15 with the spring-jack, of an auxiliary switch, connections from said switch to the spring-jack contacts and one or more wedges, all arranged to automatically change the potential of current and to change from ground to one 20 or more extended circuits by the insertion of a wedge or wedges, substantially as shown and described.
9. The combination, with a spring-jack, of 25 an auxiliary two-point switch mechanically connected to a movable jaw of the jack, generators of different potential connected respectively to the switch-points, and an electrical connection from the switch to a contact of the jack containing translating devices, as 30 and for the purpose described.
10. The combination, with a spring-jack and 35 apparatus in a circuit normally completed through contact-jaws of the spring-jack, of a supplemental switch actuated by the spring-jack wedge, and connected to the circuit through the spring-jack, and a branch or separate office-circuit connected to a wedge of the spring-jack, as and for the purpose described.
11. The combination, with two spring-jacks 40 normally completing the circuits of different sets of apparatus, of a grounding-switch interposed between one side of the apparatus and a generator which finds circuit normally through the apparatus and the normally-closed 45 spring-jack contacts.
12. In an electric switching apparatus, the combination of a spring-jack normally connected to one potential, a normally-open contact-point connected to a switch carrying 50 generators of varying potential, and a wedge connected to branch circuits arranged to automatically change the relations of the circuits, with circuit making and breaking switches L and L' placed in the local circuit, 55 substantially as shown and described.
13. The combination, with the spring-jack, of a circuit making and breaking switch in the connection from a contact of the jack to the return-circuit, and connections from said 60 contact to a switch in the circuit leading through the translating devices to the opposite contact of the spring-jack, as and for the purpose described.
14. The combination, with the grounded 65 line containing a relay-instrument, of the local circuit also grounded and having its dynamo and receiving apparatus connected to the front stops of the relay, the relay-lever itself being connected directly to ground, as and for 70 the purpose described.

Signed at New York, in the county of New York and State of New York, this 6th day of June, A. D. 1889.

FRANCIS W. JONES.
